ROLLER CORE DRILL

Filed Aug. 2, 1926

UNITED STATES PATENT OFFICE

LOUIS H. WELLENSIEK, OF HOUSTON, TEXAS, ASSIGNOR TO HUGHES TOOL COMPANY,
OF HOUSTON, TEXAS, A CORPORATION OF TEXAS

ROLLER-CORE DRILL

Application filed August 2, 1926. Serial No. 126,470.

My invention relates to core drills for use particularly in hard formation and having rolling cutters thereon.

Core drills have been constructed before with rolling cutters thereon arranged to cut an annular hole about the core, but although some such drills will cut the formation, experience has shown that a good core cannot be thus obtained with the old type of roller core drill. The reason is that the rolling cutters cause a large amount of vibration and side sway of the drill head in performing the cutting operation, and the core is broken up and worn away to such an extent that it cannot be engaged by the core catcher and removed with the bit from the hole.

It is an object of my invention to provide a roller core drill, on which the cutters are so mounted that there will be a minimum of vibration, thus leaving a full sized unbroken core which can be readily removed.

It is desired that the cutters be mounted to cut the wall of the hole smoothly and evenly and to cut a clearance about the core so that the drill will work straight in the hole and not stick in the formation as in order to present the cutters in the proper manner a special construction of the head, pins and attaching means is required. The manner of mounting the cutter shafts is also a feature of value.

Referring to the drawing herewith, Fig. 1 is a side elevation of a drill bit equipped with my invention, parts being broken away in central longitudinal section. Fig. 2 is a bottom plan view and Fig. 3 is a broken enlarged section on the plane 3-3 of Fig. 2. Fig. 4 is a transverse section through a hole being drilled showing diagrammatically the zones traversed by the inner and outer cutting rollers and also the inclination of the axes of the cutters from a horizontal plane. Like numerals of reference are employed to designate like parts in all the views.

The head 1 of my drill is a tubular body having a threaded box 2, at the upper end to connect with a drill collar 3 for operation. The interior of the head is threaded at 4 to receive the collar 5 of a core barrel 6.

Below the core barrel the inner wall of the head is tapered downwardly to provide a seat 7 for the core catcher 8. Said core catcher has toothed jaws thereon to engage and hold the core when the drill is elevated.

My invention lies particularly in the arrangement and form of the cutters. I arrange the said cutters in sets of three, and this is a most important feature in that it gives for each set of cutters a three point support which prevents vibration. There are three cutters 9 to cut the inner wall of the hole. They are arranged symmetrically in radial position on the head and rotatable on pins 10 which, as shown in Fig. 1, are inclined slightly upwardly toward the center of the bit. The head 1 has a specially constructed lower face 25.

This face is formed into six almost distinct segments 26 and 26' which are separated by the grooves 21. Each alternate segment is identical as there are three segments 26 for the inside cutters 9 and three segments 26' for the outside cutters 13, as best seen in Fig. 2. The segments 26 each have an inverted U shaped kerf 28 formed centrally thereof and opening in from the bottom. These kerfs each have a sloping surface 29 which merges with a shoulder 30. The segment 26 also has formed therein an outwardly sloping pocket or slot 19 which is spaced radially inward from the kerf 28; said pocket is constructed in the head so that it leaves but a very thin supporting portion 32 which terminates short of the lower face 25.

The pins 10 have only one support on the lower side and that is at the outer end which is provided with a flange 11 the outer portion of which is reduced in diameter. The flange 11 is adapted to accurately seat upon

the shoulder 30 in order to obtain correct placement of the cutter 9. After the pin 10 has been thus located the space about the pin in the kerf 28 is filled with welding material 12 so that the pin is thereafter internally attached to the segment 26 of the head 1. At the inner end of the pin 10 the supporting portion 32 is adapted to form a bearing seat about substantially one-half of the pin as seen in Fig. 1. In this manner the pin 10 carrying the cutter 9 is arranged to withstand the enormous loads which are imposed upon it in present day drilling operations. There is little or no downward pull upon the cutters or pins so that when the pin is seated at 32 and located in the kerf with the bond 12 of welding material it is secured firmly in the head.

The cutters 9 are rotatable in slots 19 in the head and have a bearing on the inner cylindrical end of the pin. They have a tapered periphery to engage and cut the formation. The taper of the cutters is such as to bring the apex at the central axis of the hole, so that said cutters will have a true rolling motion.

The outer cutters 13 are mounted in a similar symmetrical position radially of the head. They are rotatable on pins 14,—see Fig. 3—which are inclined downwardly toward the center. These pins 14 are firmly retained by the segment 26' which is formed somewhat like the segment 26 but with the structure reversed as the slots or pockets 18 slope inwardly. An inverted U shaped kerf 28' is formed in the outer surface of the segment and has a sloping surface 29' and shoulder 30', the same as the construction for the inwardly sloping cutters 9. The pin 14 thus is adapted to be secured firmly in the kerf 28' by means of the welding material 16. The outer end of the pin 14 has a flange 15 fitting within a recess 40 in the cutter and also adapted to seat on the shoulder 30'. The extreme outer end of the pin 14 is reduced to form a larger bonding surface in addition to the sloping face 29', and a bond 16 of welded material above said flange fixes the pin in the head.

The means used to secure the inner ends of the pins 14 is somewhat different from that of the alternate pins 10. I have resorted to this difference as the outer cutters are subjected to greater stresses and torque and travel at a greater speed than the inside cutters. The segment 26' as recited has the pocket 18 therein but a substantial portion of the segment remains as at 41, Figs. 2 and 3; said portion adjacent its base has a circular opening 17 therein which is formed at the proper inclination to receive the pin 14 when the flange 15 is properly seated at 30'. The pin 14 is preferably beveled as at 42 so that proper clearance may be had for the loose material from the cutters 9.

The cutters 13 are of larger diameter than the cutters 9 and are toothed to cut the material and are tapered and positioned to produce a true rolling motion. The said cutters 13 fit in slots 18 in the head which serve to house the upper sides of said cutters.

The flushing water is discharged directly into the slots 18 and 19 upon the cutters, through channels 20 in the bit head, said channels connecting with the interior of the head above the collar 5 of the core barrel.

It will be noted that the inner set of three symmetrically arranged cutters will cut the inner wall of the hole and being of smaller diameter will provide space for the inner ends of the cutter pins 14 on the other set of cutters. The outer cutters, in their turn cut the outer part of the hole and provide clearance for the cutter pins 10 and their supports.

A core drill, constructed as set out above, works smoothly and evenly and will take a full sized core without failure where the older types will rarely, if at all, bring out a core. This is due to a combination of two features; the symmetrical three-point support, and the tapering and mounting of the cutters to give them a true rolling motion. The present core bit has been evolved as the result of much experimentation and the means and method of securing the pins and cutters to the head has been resorted to only because sufficient clearance and rigidity are then obtainable.

In operation, the bit is rotated to roll the cutters upon the bottom of the hole. The inner set of cutters cuts an annular track around the core, and being supported at three evenly spaced points, they roll without vibration. The outer set of three also cuts an annular track about the outer side of the hole, the two tracks cut by the different sets forming an annular path extending inwardly and upwardly as clearly shown in Fig. 4. The flushing water washes the cutters free of material which is carried upwardly through grooves 21 on the outer face of the head, and around the drill stem to the surface.

Having thus described the invention, what I claim as new and desire to protect by Letters Patent is:

1. A roller core drill including a tubular head, a set of three symmetrically arranged inwardly tapered roller cutters mounted on the face of said head on shafts upwardly and inwardly inclined to form a bias cut, a second set of three symmetrically arranged inwardly tapered roller cutters mounted in said head intermediate the first set and radially outward relative thereto, said second set of cutters being disposed on shafts inclined upwardly and outwardly of the head, and means to integrally secure said shafts to said head to form a bias cut angular with respect to the first mentioned cut.

2. In a roller coring bit, a head, a plurality of radial segments thereon, a pocket in each of said segments, a cutter disposed in each of said pockets, a shaft upon which said cutter is rotatable, a kerf in said segment, a shoulder in said kerf, a flange on said shaft adapted to seat on said shoulder, welded material fitting said kerf and integrally bonding said pin and said segment. 70
3. A roller core drill including a tubular head, a plurality of inwardly tapered roller cutters arranged for true rolling cutting action having axes inclined with respect to the axis of the head and cutting edges inclined to cut angularly related surfaces for the hole, the axis of each cutter forming one surface being differently inclined toward the axis of the head than the axis of the cutter forming another surface, and means for integrally securing the cutters to the head within the path of the cut. 75
4. A roller core drill including a tubular head, two sets of three alternately spaced inwardly tapered roller cutters, each arranged for true rolling cutting action, the axes of one set being inclined downwardly toward the axis of the head and the axes of the other inclined upwardly toward the axis of said head, and means integral with said head for supporting the rollers within the path of the cut. 80
5. A roller core drill including a tubular head, two sets of three alternately spaced inwardly tapered cutters each arranged for true rolling cutting action, pins for supporting said cutters each alternately inclined downwardly and upwardly toward the axis of the head, and means for integrally securing said pins to the head within the path of the cut formed by the drill. 85
6. A roller core drill including a tubular head, two sets of alternately spaced inwardly tapering cutters arranged for true rolling cutting action, the axis of each alternate cutter being inclined downwardly and upwardly toward the axis of the head to form the outer and inner faces of the hole respectively, and the set of cutters forming the outer face being of a greater diameter than the set of cutters forming the inner face. 90
7. A roller core drill including a tubular head having a plurality of forwardly opening pockets alternately inclined downwardly and upwardly toward the axis of said head, a transverse bearing for each pocket confined within the walls of the head, inwardly tapering roller cutters with supporting shafts mounted in said pockets to take the corresponding inclination and confined between the circular walls of said head, and said shafts being secured to the bearing of the pockets by bonds of metal welding. 95
8. A roller core drill including a tubular head having a plurality of sets of three forwardly opening pockets alternately down- 100
- wardly and upwardly inclined toward the axis of said head, a transverse bearing for each pocket confined within the side walls of the head, inwardly tapering roller cutters with supporting shafts mounted in said pockets to take the corresponding inclination and confined between the circular walls of said head, and said shafts being secured to the bearings of the pockets by bonds of metal welding. 105
